(57) **CLAIM**

The ornamental design for a spray cap, as shown and described.

DESCRIPTION

FIG. 1 is a perspective view of a spray cap in accordance with the present invention in a closed configuration; FIG. 2 is a front view of the spray cap of FIG. 1;

FIG. 3 is rear view of the spray cap of FIG. 1; FIG. 4 is a side elevational view of a first side of the spray cap of FIG. 1;

FIG. 5 is a side elevational view of a second side of the spray cap of FIG. 1; FIG. 6 is a top plan view of the spray cap of FIG. 1;

FIG. 7 is a bottom plan view of the spray cap of FIG. 1; FIG. 8 is a perspective view of the spray cap of the present invention in an open configuration;

FIG. 9 is a front view of the spray cap of FIG. 8; FIG. 10 is rear view of the spray cap of FIG. 8;

FIG. 11 is a side elevational view of a first side of the spray cap of FIG. 8;

FIG. 12 is a side elevational view of a second side of the spray cap of FIG. 8;

FIG. 13 is a top plan view of the spray cap of FIG. 8; and, FIG. 14 is a bottom plan view of the spray cap of FIG. 8. The broken lines depict portions of the spray cap that form no part of the claimed design.
